UNITED STATES PATENT OFFICE.

ALBERT D. BARTLETT, OF WASHINGTON, DISTRICT OF COLUMBIA.

LOCKING DEVICE FOR ELECTRIC LAMPS, &c.

1,092,627.

Specification of Letters Patent.

Patented Apr. 7, 1914.

Application filed June 9, 1913. Serial No. 772,724.

To all whom it may concern:

Be it known that I, ALBERT D. BARTLETT, a citizen of the United States, residing at Washington, in the District of Columbia, 5 have invented new and useful Improvements in Locking Devices for Electric Lamps, &c., of which the following is a specification.

This invention relates to an improved 10 locking device for electric lamps, separable connectors, and the like.

It is a common experience in large establishments, where numerous incandescent lamps are used, and to which dishonest and 15 irresponsible people have access, to have the lamps removed from their sockets by unauthorized persons, resulting in a pecuniary loss of considerable magnitude. It is also not unusual to have the parts of detachable 20 connectors of various other types removed or tampered with, likewise resulting in loss of the parts and derangement of the electric system, inflicting further damage upon the owners or operators of the installation.

25 One of the objects of the present invention is to provide simple means for normally preventing the separation of a lamp, or other removable connector, from its socket, except by authorized persons.

30 A further object is to provide means of this character which are electrically controlled.

35 A further object is to provide means which are also selectively controlled, whereby the means which will permit removal of the lamps, or the like of one installation, will not operate in connection with those of another installation.

40 The invention will be hereinafter fully set forth and particularly pointed out in the claims.

In the accompanying drawing:—Figures 1 and 2 are side views taken at right angles to each other, illustrating a lamp socket 45 with my invention applied thereto, the casting being shown in section. Fig. 3 is a top plan view of the socket. Fig. 4 is a top plan view of the screw shell removed from the socket. Fig. 5 is a longitudinal sectional view on the line 5—5, Fig. 3. Fig. 6 is a similar view on the line 6—6, Fig. 3. Fig. 7 is a view illustrating the resistance key. Fig. 8 is a detail illustrating a slight modification. Fig. 9 is an enlarged detail view 50 illustrating the solenoid.

Referring to the drawing, 10 designates a

porcelain lamp socket which may be of any suitable or preferred type, the form illustrated being arbitrarily selected for illustrative purposes only. Said socket, as illustrated, is provided with a central chamber 11 in which is located the bearing member 12 in which is rotatably mounted the key shaft 13 provided with the usual key 14. Said bearing member is held in position by means of a screw 15 extending through a suitable bore 16 centrally located with respect to said block. Said bearing member 12 is also provided with an ear 17 to which the terminal of one of the electric conductors or line wires 18 is connected in the usual manner. The porcelain block 10 is also provided with a second chamber 18' which intersects the chamber 11, and in which is located the bearing member 20 to which the screw shell 21 is swiveled by means of the rivet or pin 22, the latter also serving as the usual central contact for the lamp 23. The swivel-bearing member 20 is secured in position by means of screws 24 extending through the block 10, and the same is provided with an upstanding lug 25 to which the end of the other conductor or line wire 26 is secured. In the operation of the lamp, the circuit is closed by the key 14, one end of which contacts with the end wall of the shell 21, and the other end with a spring arm 27 secured to the bearing member 12. The construction above described is well known and I do not care to limit myself to its use.

In carrying out my invention I provide the block 10 with a bore near the periphery thereof, and locate in said bore a small solenoid coil 30, the lower end of which is provided with a flange 31 which abuts against a complementary shoulder formed in the bore. One terminal of said solenoid is connected with the screw 15, by a wire 32 thereby placing the solenoid in circuit with the line wire 18. The other terminal of the solenoid is connected with a contact 33 embedded in the circular surface of the block 10. A second contact 34 is similarly embedded in the block 10 adjacent contact 33, and is connected by a suitable wire 35 with one of the screws 24, whereby said contact 34 is placed in circuit with the line wire 26. The core 36 of the solenoid constitutes the locking member, and comprises a rod of magnetic material having a head at one end against which bears a retracting spring 37 which acts against a

suitable abutment. The other end of said rod is provided with a short length of non-magnetic material which is designed to enter complementary openings 38 in the end 5 wall of shell 21 to prevent rotation of the latter on the swivel pin 22. In operation the spring normally holds the core 36 retracted so that the shell 22 may freely turn on its swivel. When the circuit is closed 10 across contacts 33 and 34 the solenoid coil is energized, moving the core against the action of the spring 37, causing the non-magnetic end of the core to enter one of the openings 38, thereby locking the shell 21 15 against rotation. While thus locked the lamp may be screwed into the shell or removed, as the case may be. As soon as the circuit is broken at the contacts 33, 34, the core 36 is again retracted, permitting the 20 shell 21 to turn on its swivel, thereby frustrating any attempt to remove the lamp as the screw shell will turn therewith. The casing of the lamp socket covers the shell 21 and thereby prevents access to the shell 25 in any manner.

The circuit may be closed at the contacts 33, 34 in any suitable manner. I prefer, however, to employ a resistance key such as illustrated in Fig. 7. Said resistance key 30 comprises a casing 40 in which is located a resistance coil 41 having terminals 42 which may be placed in engagement with contacts 33 and 34. The end of casing 40 from which the terminals 42 project, is preferably concaved, as indicated at 43, so as to form a seat for the convexed wall of the socket casing surrounding the block 10, thereby preventing wobbling of the key when it is desired to operate the solenoid.

40 The contacts 33, 34, may, if desired, be arranged flush with the surface of the block 10 as illustrated in Fig. 6, the socket casing being provided with insulated openings 44 through which the terminals 42 of the resistance key may project. Or, said block 10 may be provided with teats or protuberances 45 through which the contacts 33, 34, extend, the socket casing being slotted to permit the parts to be assembled. It is obvious 50 that the windings of the solenoid 30 and those of the resistance key may be so relatively varied that the solenoid will only respond to a circuit closed through a resistance key having a predetermined winding. In 55 this manner each installation will be provided with a key which will not operate in conjunction with any other installation, and said installation will not respond to any other key.

60 In order to prevent the inclosing casing surrounding shell 21 from being squeezed in sufficiently to prevent rotation of said shell, I provide a suitable reinforcement for said casing. For instance, in the drawings I 65 have shown said casing as provided with an

offset annular portion 46 in which is secured a steel reinforcing band 47 of sufficient strength to resist any pressure tending to squeeze the casing against the shell for the purpose of preventing rotation of the latter. 70 In this manner I guard against removal of the separable member except by one possessing the proper resistance key.

Having thus explained the nature of my invention and described an operative manner of constructing and using the same, although without attempting to set forth all of the forms in which it may be made, or all of the forms of its use, what I claim is:—

1. In a locking device for electric lamps, an insulating block, and an electric locking device carried thereby comprising a bolt, a spring coil for holding said bolt normally retracted, and a magnetic coil for projecting 85 said bolt in opposition to said spring, in combination with a screw shell having one end wall swiveled to one end of said insulating block, the end wall of said shell being provided with complementary means to 90 be engaged by said bolt.

2. In a locking device for electric lamps, an insulating block, and an electric locking device embedded therein and comprising a reciprocable bolt, a spring coil for holding 95 said bolt normally retracted, and a magnetic coil for projecting said bolt in opposition to said spring, in combination with a shell having one end wall swiveled to one end of said insulating block, the end wall of said shell being provided with complementary means spaced from the periphery thereof to 100 be engaged by said bolt.

3. In a locking device for electric lamps, an insulating block, and an electrically operated bolt carried by said insulating block, in combination with a screw shell having one end swiveled to one end of said insulating block, the end wall of said shell being provided with complementary means to be 105 engaged by said bolt.

4. In a locking device for electric lamps, an insulating block, and an electric locking device carried thereby comprising a bolt, a spring coil for holding said bolt normally 115 retracted, and a magnetic coil for projecting said bolt in opposition to said spring, in combination with a screw shell having one end wall swiveled to one end of said insulating block, the end wall of said shell being provided with complementary means to be 120 engaged by said bolt, and means independent of the lamp for controlling the circuit to said coil.

5. A locking device of the character described comprising an insulating block, a shell swiveled thereto, and electrically operated means for preventing relative rotation of said block and shell, in combination with an electrical member independent of 125 130

said lamp for controlling the circuit to said electrically operated means.

6. A locking device of the character described comprising an insulating block, a shell swiveled thereto, a solenoid located within said block and provided with a core arranged to engage said shell, in combination with an electrical member independent of said lamp for controlling said solenoid.
- 10 7. In a locking device for electric lamps, an insulating block, lamp contacts therein, line wires leading to said contacts, and an electric locking device carried by said block and electrically connected with said line wires in combination with a screw shell having one end wall swiveled to one end of said insulating block, the end wall of said shell being provided with complementary means to be engaged by said locking device.
- 15 8. In a locking device for electric lamps, an insulating block, lamp contacts therein, line wires leading to said contacts, a solenoid coil carried by said socket and connected with said line wires, and a bolt forming the core of said solenoid, in combination with a screw shell having one end wall swiveled to one end of said insulating block, the end wall of said shell being provided with complementary means to be engaged by
- 20 30 said bolt.
9. A locking device of the character described comprising an insulating block, a shell swiveled thereto, electrically operated means for preventing relative rotation of said block and shell, and means normally detached from said block and said shell for

closing the circuit to said electrically operated means.

10. A locking device of the character described comprising an insulating block provided with contacts, line wires leading to said contacts, a shell swiveled to said block, electrically operated means for preventing relative rotation of said block and shell, and means normally detached from said block and said shell for closing the circuit from said line wires to said electrically operated means.

11. The combination with a key socket, and line wires leading thereto, and a screw shell having one end swiveled to one end of said socket, of a bolt for preventing relative rotation of said key socket and said shell, means for holding said bolt normally retracted, and electrical means in circuit with said line wires for moving said bolt in opposition to its retracting means.

12. The combination with a key socket and a screw shell swiveled thereto, of a locking member for preventing relative rotation of said socket and shell, a casing inclosing said parts, and a reinforcing ring engaging the inner wall of said casing and surrounding said shell to prevent crushing of the latter.

In testimony whereof I have hereunto set my hand in the presence of two subscribing witnesses.

ALBERT D. BARTLETT.
